Specification of Letters Patent.

Patented Apr. 6, 1915.

Application filed March 31, 1914. Serial No. 828,545.

To all whom it may concern:

Be it known that I, BURTON H. CLEMENT, a citizen of the United States, residing at Beloit, in the county of Rock and State of Wisconsin, have invented a new and useful Lathe, of which the following is a specification.

This invention has reference to improvements in lathes, and its object is to provide a small, compact, screw-cutting and wood-turning lathe capable of doing accurate work, and yet one of extreme simplicity and relatively cheap construction having certain advantages which will hereinafter appear.

In accordance with the present invention the working parts of the lathe are mounted on a rockable bed so that chips or shavings find no lodgment on any part of the bed, but at once fall out of the way, wherefore the lathe is particularly clean in operation. Moreover, the rockable bed forms an efficient belt tightener and is particularly valuable in connection with a foot power drive.

The improved lathe provides back gearing, which in conjunction with readily interchangeable feed screws constitutes the lathe a screw-cutting lathe of efficiency.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention as set forth in the claims.

In the drawings:—Figure 1 is an end elevation of a lathe embodying the present invention. Fig. 2 is a plan view of the lathe with distant parts omitted. Fig. 3 is a front elevation of the lathe with parts below the bed in the main omitted. Fig. 4 is a section on the line 4—4 of Fig. 1. Fig. 4^a is an elevation of a modification of a detail of the construction. Fig. 5 is a section on the line 5—5 of Fig. 4. Fig. 6 is a section on the line 6—6 of Fig. 2 with distant parts omitted. Fig. 7 is a section on the line 7—7 of Fig. 4,

some distant parts being omitted. Fig. 8 is a section on the line 8—8 of Fig. 4 with 55 distant parts omitted. Fig. 9 is a section on the line 9—9 of Fig. 3 with distant parts omitted. Fig. 10 is a fragmentary section on the line 10—10 of Fig. 3. Fig. 11 is a section on the line 11—11 of Fig. 10. Fig. 60 12 is a detail elevation of a ring mounted on the tool carriage.

Referring to the drawings, there is shown a bed 1 of general tubular form with terminal reduced extensions 2 adapted to cap plates 3, which latter have expanding leg portions 4 channeled for the reception of legs 5 upon which the end plates and bed 1 with parts carried thereby, and which are to be described, are sustained.

At suitable points about midway of the length of the legs 5 at each end of the lathe, these legs are connected by a cross piece 6 suitably fastened to the legs to aid in keeping them from spreading, and each cross 70 piece 6 at one end is formed with a bearing for a shaft 7 upon opposite ends of which are mounted wheels 8 and 9, respectively, the wheel 8 being suitably grooved for the reception of a belt 10, and the wheel 9 being 75 located at the other end of the machine serving conveniently as a fly-wheel. Extending between what may be termed the front legs of the two pairs of legs of the machine and near the lower ends of these 80 front legs, is a rod 11 upon which are mounted treadles 12 connected by links 13 to respective wheels 8 and 9, so that the shaft 7 with the wheels 8 and 9 may be conveniently rotated by the operator.

Extending through the cap plates 3 and axially through the tubular bed 1 is a rod or bolt 14 having a head 15 at one end and a nut 16 at the other end, the bolt serving to hold the cap plates and bed together, 95 but permitting the turning of the bed about its longitudinal axis, this being done by loosening the nut 16, and the bed is held in any desired position of adjustment about its longitudinal axis by tightening the nut 16.

At one end the bed 1 is provided with a head stock 17 and at the other end with a tail stock 18, and these parts may be cast in one piece with the bed, or if desired may be separately cast and secured to the bed 100 in any suitable manner, so as to be in effect

in one piece therewith. Ordinarily the tail stock of the lathe is made adjustable toward and from the head stock, but in the lathe of the present invention this is not done, for the tail stock is effectively in one piece with the bed, and located permanently with relation thereto, while provision is made for adjustments usually brought about in lathes by movements of the tail stock.

10 The head stock and tail stock adjacent to the bed have alined bores or passages 19, 20, respectively, and at respectively opposite ends of the bores the head stock is provided with an annular flange 21 in alinement with the bore 19, and the tail stock is provided with an annular flange 22 in alinement with the bore 20.

15 The head stock has at the end remote from the bed 1 an angular extension 23 from which there projects a yoke 24 having an angular leg 25 spaced from the head stock on the side thereof remote from the tail stock and returned toward the prolongation of the longitudinal axis of the alined passages 19 and 20, where the leg 25 terminates in a bearing 26.

20 Extending through the passages 19 and 20 and long enough to project beyond the flanges 21 and 22 is a hollow shaft 27 provided where extending through the passage 20 with an elongated key way 28. The shaft 27 carries a rotatable sleeve 29 counterbored at one end, as shown at 30, to receive the flange 21, and on its exterior surface provided at the said end with a circular series of gear teeth 32, these teeth constituting a gear pinion. The sleeve 29 extends through and is supported by the bearing 26 at the corresponding end of the leg 25, and beyond 25 this bearing has an extension 33 of reduced diameter and terminates in an inturned annular flange 34 providing a passage of substantially the same bore as the interior of the tubular shaft 26, and in alinement therewith. The shaft 27 is designed to receive a rod 35 having one end extending through the annular flange 34 where it is held by a set screw 36 which may be in the form of a thumb screw, or may be any type of screw 30 suitable for holding the rod 35 firmly to the sleeve 29, but permitting the ready withdrawal of the rod from the sleeve 29 and shaft 27 when desired. The rod 35 is of sufficient length to extend about to the tail stock and for an appropriate portion of its length between the head and tail stocks is screw-threaded, as shown at 37. For reasons which will hereinafter appear the lathe 35 may be furnished with a suitable number of such screw rods, each of an appropriately different pitch from that of the others.

30 Mounted on the reduced end 33 of the sleeve 29 is a gear wheel 38 from one face of which there projects a hub 39 snugly yet freely fitting the prolongation 33 and pro-

vided with a longitudinal slot 40 through which there is extended a set screw 41 threaded into the extension 33 so that the gear wheel 38 may be adjusted lengthwise of the extension 33 for a distance regulated by the length of the slot 40, while a thumb screw 41 forms a convenient means for holding the gear wheel in adjusted positions.

35 In operation the head and tail stocks extend upwardly and rearwardly with respect to the position occupied by the operator, which is at the right hand side of the machine as illustrated in Fig. 1. At a higher point in the head stock than the passage 19 is another passage 42 parallel with the passage 19 and at the respectively opposite ends of this passage are annular flanges 43 and 44, respectively. In line with the passage 42 the tail stock has a passage 45 therethrough, this passage terminating in annular flanges 46, 47, respectively, while from the flange 47 there is rearwardly inclined extension 48 of the tail stock through which is produced a threaded passage 49 parallel with the passages 20 and 45 and prolonged by terminal flanges 50.

40 The passage 45 is provided with a rod 51 which projects toward the head stock and at the end toward the head stock is formed with a tapered socket 52 for a taper center 53. Near the inner end of the socket 52 the rod 51 is provided with a transverse slot 54 so that the center 52 may be readily dislodged by the insertion of a suitable tool through the slot 54.

45 The threaded passage 49 has an exteriorly screw-threaded rod 55 extending therethrough, this rod having at the end toward the head stock an axially tapered socket 56 for a taper center 57, and at the other end the threaded rod 55 carries a crank disk 58 provided with a crank handle 59 for the ready turning of the screw rod. The rod 55 near the crank disk 58 has a smooth section 60 which is journaled in a bearing 61 at one end of a block 62, the other end 63 of which is split and shaped to embrace the corresponding end of the rod 51 and is made to bind on the rod 51 by means of a screw 64 provided with a manipulating handle 65. The screw rod 55 serves as a means for moving the rod 51 through the passage 45 to thereby adjust the center 53 toward and from the head stock, the center 57 participating in such movement, but if it be desired to adjust the center 57 without movement of the center 53 the clamp end 63 of the block 62 is loosened from the rod 51, whereupon the screw rod 55 may be moved lengthwise without corresponding movement of the rod 51. Moreover, by loosening the clamp end 63 of the block 62 the rod 51 may be removed entirely from the tail stock if such be desired.

50 Mounted on the flange 22 is a sleeve 66

held to its flange by a set screw 67 extending through a circumferentially disposed slot 68 in the sleeve 66, and this sleeve beyond the flange 22 is of reduced internal diameter 5 to fit the shaft 27 snugly yet freely, and within the sleeve 66 there is lodged a key or spline 69 entering the groove 28 of the shaft 27.

The sleeve 66 close to the tail stock is 10 formed with a gear segment 70 in mesh with which there is a worm section 71 on a worm shaft 72 having a supporting bearing 73 in an extension 74 of the flange 47, the shaft 72 being provided with an annular groove 15 75 in which is lodged a pin 76 traversing the bearing 73, so that the shaft may be turned without progressive movement. That end of the shaft 72 remote from the bearing 73 is provided with a crank disk 77 carrying a 20 crank handle 78, whereby the shaft may be rotated as desired to thereby actuate the gear segment 70 and thus rock the sleeve 66 in one direction or the other, the hollow or tubular shaft 27 participating in this rock- 25 ing movement for a purpose to be described.

Extending through the passage 42 in the head stock and an alining passage 79 in the leg 25 is a tubular shaft 80, one end of which extends beyond the flange 44 and there carries a gear wheel 81 constituting a face plate and provided with the usual radial 30 slots 82 for the reception of the tail end of a lathe dog. That end of the shaft 80 carrying the gear wheel or face plate 81 is 35 shaped for the reception of a center 83 in alinement with the center 53. The other end of the shaft 80 extends beyond that face of the leg 25 remote from the head stock and there is formed with an annular series of 40 gear teeth 84 forming a gear pinion in position to mesh with the gear wheel 38 when the latter is moved toward the leg 25 and the shaft 80 is disconnected from the gear wheel 38 when the latter is moved away from 45 the leg 25 to the extent permitted by the slot 40. Between the head stock 17 and the leg 24 the shaft 80 carries a gear pinion 85 made fast to the shaft by a set screw 86 or otherwise, and the gear wheel or face plate 50 81 is made fast to the corresponding end of the shaft 80 by a set screw 87 or in any other suitable manner.

The angle prolongation 23 of the head stock has a passage 88 therethrough parallel 55 with the other passages through the head stock and the leg 25 has a similarly located passage 89 therethrough in alinement with the passage 88. Extending through and mounted in these two passages is a shaft 90 60 formed where passing through the leg 25 with spaced annular grooves 91, 92, respectively. Mounted on the shaft 90 between the head stock and the leg 25 is a gear wheel 93 having a pulley 94 formed on one side 65 thereof. The gear wheel 93 is made fast to

the shaft 90 in any suitable way so as to move therewith both longitudinally and rotatively. That end of the shaft 90 remote from the grooves 91 and 92 has a pinion 95 fast thereto in position to mesh with the gear wheel 81, but the shaft 90 is capable of longitudinal movement to carry the pinion 95 out of mesh with the gear wheel 81. That end of the shaft provided with the pinion 95 is axially adapted for a threaded 70 75 center pin 96 on a supporting plate 97 having its center in line with the center 57.

The leg 25 has an angle extension 98 on which there is mounted by a pivot 99 a latch arm 100 lying close to the inner face of 80 the leg 25 and movable into and out of the grooves 91 and 92 through a notch 101 formed in a flange 102 on the inner face of the leg 25 and surrounding the passages 89. By this means the shaft 90 may be adjusted lengthwise and held in the adjusted 85 positions. When the latch 100 is in the groove 92, the pinion 95 is in mesh with the gear wheel 81 and when the latch is in the groove 91 the pinion 95 is moved out of 90 mesh with the gear wheel 81. When the shaft 90 is so positioned that the pinion 95 is out of mesh with the gear wheel 81, the gear 93 is in mesh with the pinion 85 but is out of mesh therewith when the pinion 95 95 and gear 81 are in mesh.

Pivotedly mounted on the flange 21 close to the corresponding face of the head 17 is an arm 103 extending rearwardly with respect to the head and at the free end of 100 this arm there is pivoted a latch arm 104 terminating in a handle 105, this latch arm extending through the space between the head 17 and leg 25 toward the front of the lathe. The flange 43 is provided wth a tooth 106 105 best shown in Fig. 6, and the arm 104 is provided with notches 107 any one of which is adapted to receive the tooth 106, thus holding the arm 103 in different adjusted positions. The arms 103 and 104 are connected by a spring 108 tending to hold the arm 104 with the tooth 106 entering one of the notches 107. The arm 103 has extensions 109, 110 on opposite sides of its pivot support upon the flange 21. The extension 109 110 carries a stud 111 upon which is mounted a gear pinion 112 so positioned that on a suitable rocking of the arm 103 this pinion will mesh with the pinion 85 and is at all times in mesh with the pinion 32. The extension 120 110 is provided with studs 113, 114 carrying respective pinions 115 and 116 at all times in mesh with each other, while the pinion 115 is at all times in mesh with the pinion 32. On rocking the arm 103 in the 125 direction to move the pinion 112 out of mesh with the pinion 85, the pinion 116 may be brought into mesh with the pinion 85, but because of the presence of two pinions 115 and 116, the motion transmitted thereby to 130

- the pinion 32 will be the reverse of that transmitted by the pinion 112. These two engaging positions are represented by the end notches of the series of notches 107, 5 there being three such notches, while the middle notch represents a position of the arm 103 when neither pinion 112 nor 116 is in engagement with the pinion 85. The various positions of these pinions, which together with the pinions 112, 115 and 116 10 constitute the reverse gear of the lathe, will be best understood by reference to Figs. 5 and 6. The pulley 94 is connected to the drive wheel 8 by the belt 10.
- 15 Mounted upon the hollow or tubular shaft 27 between the head and tail stocks is a block 117 constituting the body of the tool carriage of the lathe, and this block is formed with the usual undercut slot 118 20 for the headed stem 119 of the customary tool post 120, which latter needs no description, as it may follow the usual practice. The tool carriage 117 is held firmly to the hollow shaft 27 by a set screw 121.
- 25 At one end the block 117 has an axial prolongation 122 adjacent to which the tool carriage or block is formed with a boss 123 having a passage 124 therethrough radial to the shaft 27, and the latter is pierced 30 by a radial passage 125 in line with the passage 124 to receive the threaded end 126 of a feed nut in the form of an elongated block 127 adapted to the passages 124 and 125, while the threaded end of this nut is adapted 35 to the threads of the threaded end 37 of the rod 35.
- 40 The prolongation 122 of the tool carriage is formed with a seat for a ring 128 surrounding the shaft 27, and the edge of this ring is milled as shown at 129, Figs. 2 and 3, for convenient manipulation. One side face of the ring 128 is formed with a spiral groove 130 receiving a pin 131 projecting from the block 127, and extending through 45 the prolongation 122 of the tool carriage is a set screw 132 in position to engage that face of the ring 128 remote from the groove 130 to hold the ring against rotation when desired. By loosening the screw 132 the 50 ring 128 may be rotated and the spiral groove 130 will cause the nut block 127 to move into or out of engagement with the screw end 37 of the rod 35, so that the carriage may be fed by the rotation of the 55 screw rod 35, or this feeding may be stopped whenever desired. Since the tool carriage 117 is made fast to the shaft 27 the feeding of the carriage by the screw end 37 of the rod 35 is participated in by the shaft 27 60 which under such circumstances merely moves lengthwise, but does not rotate. This shaft or tube may be rocked, however, by manipulation of the crank 78 to an extent permitted by the length of the slot 68 in the sleeve 66, and this rocking movement 65

causes a similar movement of the tool carriage thereby feeding the tool toward or from the work, which is assumed to be held between the centers 53 and 83.

Since the tail stock is stationary, small 70 work can be held between the centers 53 and 83 only by moving the rod or tail stock spindle 51 for a considerable distance beyond its support in the tail stock. Under such circumstances the use of a steady-rest is desirable, and such steady-rest is shown in the drawings as constituting a sleeve 133 carried by a post 134 terminating in a base portion 135, best shown at Fig. 9, adapted to under- 75 ride the bed 1 and be secured thereto by a set screw 136. In order to lock the tail stock spindle 51 against lengthwise movement a set screw 137 is provided on the sleeve 133 in position to engage the spindle 51 and so lock it in place. 80

In order to compact and cheapen the structure without sacrifice of accuracy or efficiency, all boxings are avoided, and in their place wear take-up means are provided. Since all the wear take-up means are substantially alike, but one of them will be described in detail, and this with reference to Fig. 8. In transverse relation to the passage 49 there is another passage 138 in which is mounted a block 139 preferably, though not necessarily, of cylindrical form, and this block has transversely therethrough a passage 140 slightly larger in diameter than the passage 49 and sufficiently large to permit the screw rod 55 to move freely therethrough. 90 The block 139 is controlled by a set screw 141 which in the particular showing of Fig. 8 has a manipulating head 142 of familiar form, but any other suitable means for adjusting the block 139 may be employed. 100 These blocks are all comparatively large with respect to the bearings for the various parts they control, so that in the case of wear a slight turn of the screw 141 tends to take up all such wear, forcing the turning parts always toward the same side of the bearings, and thus keeping them constantly in workable alignment. Besides the block 139 there are similar blocks 143, 144, 145, 146 and 147 110 for the spindle 51, shaft or tube 27, head stock spindle 80 and shaft 90. 115

Let it be assumed first that it is desired to turn some wood or other similar substance upon the lathe. The stock is inserted between the spur plate 97 and the center 57, 120 the stock being held sufficiently tight by a suitable manipulation of the screw shaft 55, the block 62 being either allowed to remain fast to the tail stock spindle 51 or loosened therefrom. Now, with the parts in the position shown in the drawings rapid rotative movement is given to the stock, and while the head stock spindle 80 may be rotated through the meshing of the pinion 95 with the gear wheel 81, the load is not noticeable, 125 130

especially if the gear wheel 38 be moved out of mesh with the gear pinion 84, and this is the customary practice. Suppose, however, that it is desired to cut screw threads upon 5 suitable stock, such stock is mounted between the centers 83 and 53, and is connected up to the face plate or gear 81 by the employment of a suitable lathe dog. If it be desired to cut a rather fine thread, or to do common 10 turning at slow speed and high power and also slow feed, then the gear wheel 93 remains as shown in the drawings out of mesh with the gear wheel 85 and the gear pinion 95 remains in mesh with the gear wheel 81, 15 and the gear wheel 38 remains in mesh with the pinion 84, while the carriage 117 is coupled to the screw end 37 of the feed screw rod 35. Under these circumstances the work 20 is rotated with a speed corresponding to the relation of the pinion 95 to the gear wheel 81 and the tool carriage is fed along the work with a speed corresponding to the pitch of the threads of the lead screw rod 35 and the relation of the pinion 84 to the gear 25 wheel 38, the reverse gearing carried by the rock arm 103 being at this time in the neutral or inactive position. The tool on the tool carriage is moved into engagement with the work by a suitable manipulation of the 30 crank disk 77. If, now, it is desired to use higher speed for light turning or filing, the gear wheel 93 is moved into mesh with the pinion 85, thus disconnecting the pinion 95 from the gear wheel 81, and, the other 35 connections remaining as before, the work is rotated with greater rapidity because of the changed relation of the driving gearing, and the same screw threads are cut, or light common turning done.

40 If it be desired to cut right or left hand threads of the same pitch as the lead screw 35, the gear 38 is moved out of mesh with the gear 84 and the arm 104 is manipulated to bring the gear pinion 112 into mesh with 45 the gear 85, or the pinion 116 into mesh with the gear 85, as the case may be, the result being right or left hand threads in accordance with the position of the reverse gearing controlled by the arm 104. To get more power 50 and slower speed, the pinion 95 is brought into mesh with the gear 81, in which case the gear wheel 83 is out of mesh with the gear wheel 85. Still further variations may be had by removing the lead screw rod 35 and substituting one on which the threaded end 55 37 is of a different pitch, the feed nut lock 127 being also changed.

By the employment of suitable tools and regulating the cut of the tools metal may 60 be readily turned without the necessity of producing screw threads.

In order to prevent longitudinal movement of the sleeve 29 it is provided with a circumferential groove 148 where the sleeve 65 passes through the bearing 26, and this

bearing is traversed by a pin 149 in position to seat in the groove 148, thus permitting the sleeve 29 to rotate, but preventing longitudinal movement thereof. The function of the pin 149 may be performed by a pivoted 70 latch arm 150 shown in Fig. 4^a and pivoted to an ear 151 on the leg 25 adjacent to the bearing 26. Such arrangement avoids the necessity of a pin which must be driven through a hole and when it is desired to 75 dismantle the structure, it must be driven out again. With the arrangement shown in Fig. 4^a the sleeve 29 is readily released for permitting removal by simply lifting the 80 latch arm 150.

Since the bearing 26 is at the free end of the leg 25, such end of the leg 25 may spring under some circumstances, and in order to prevent this contingency there is provided a connecting bar 152 secured by screws 153 85 at the respective ends to the bearing end 26 of the leg 25 and to the head stock adjacent to the bed 1, the bar 152 preventing any springing movement of the leg 25.

While the tool carriage 117 performs in 90 general the functions of a slide rest, it is in fact carried by and moves with the tubular shaft or spindle 27, which in turn is capable of longitudinal sliding movement in the head and tail stocks, the latter being in fixed 95 relation one to the other, while the main feed screw or screw rod 35 extends through this tubular spindle 27 and causes the feeding of the tool carriage lengthwise of the lathe when the feed nut 127 is in engagement with the threaded end 37 of the feed screw. Movements of the tool toward and 100 from the work are due to the rocking movement of the sliding spindle sustaining the tool carriage, and in the particular arrangement shown in the drawings such rocking movements are determined by adjustments 105 of the worm 71 performed by hand.

In the lathe of the present invention those 110 parts holding the work are to one side of the vertical plane of the bed, and no part of the bed directly underrides the work holding members of the lathe. Because of this arrangement all chips and shavings fall 115 clear of the bed and besides all the working parts liable to clogging by chips or shavings are thoroughly protected and inclosed and the bed itself has a rounded upper surface to which chips or shavings will not 120 readily cling.

The tool carriage may be hand fed, when desired, by having the reversing gear disengaged, that is, with the drum 104 so placed that the tooth 106 engages in the central notch 107, and the gears 38 and 84 disengaged. By using the gear 38 as a hand 125 wheel and also manipulating the hand wheel 77, the carriage is moved in either direction as fast or slow as desired, and the tool is 130

moved toward or from the work. With the hand control of the tool carriage either speed may be used.

What is claimed is:—

- 5 1. A lathe provided with a bed mounted for rocking movements about its longitudinal axis, and a head stock fixed to the bed and participating in the rocking movements thereof. 70
- 10 2. A lathe provided with a bed mounted for rocking movements about its longitudinal axis, and a head and tail stock both fixed to the bed and participating in the rocking movements thereof. 75
- 15 3. A lathe provided with a bed mounted for rocking movements about its longitudinal axis and having head and tail stocks fixed to said bed. 80
- 20 4. A lathe provided with a bed having head and tail stocks permanently fixed thereto in spaced relation, the tail stock having an elongated spindle with a range of movement with respect to the tail stock substantially equal to the effective distance 85 between the head and tail stocks. 90
- 25 5. A lathe provided with a bed having head and tail stocks at and in permanently fixed relation to the respective ends of the bed and also effectively in one piece therewith, said head and tail stocks having alined 95 head and tail spindles, the tail spindle being mounted for longitudinal movement with respect to the tail stock and of a length to have a range of movement substantially equal to the effective distance between the head and tail stocks, and means for causing 100 a lengthwise movement of the tail spindle to any desired extent within its range of travel. 105
- 30 6. A lathe provided with a bed having head and tail stocks at and in permanently fixed relation to the respective ends of the bed and effectively in one piece therewith, and provided with alined head and tail stock 110 spindles, the tail stock spindle being mounted for longitudinal adjustment and of a length to have a range of movement substantially that of the distance between the head 115 and tail stocks, said tail stock being also provided with means for the adjustment of the tail stock spindle and effective thereto throughout its range of movement, and said adjusting means being of less longitudinal extent than the tail stock spindle and provided with clamping means for connecting it to the tail stock spindle at different points along the length of the latter. 120
- 35 7. A lathe provided with a bed having a head and tail stock and working parts carried thereby, supporting legs for the ends of the bed having cap plates adapted to the ends of the bed, and a securing bolt extending lengthwise through the bed and the cap plates. 125
- 40 8. A lathe provided with a bed having a head and tail stock and working parts carried thereby, supporting legs for the ends of the bed having cap plates adapted to the ends of the bed, and a securing bolt extending lengthwise through the bed and the cap plates, the bed and cap plates being coactively formed to permit rocking movements of the bed in the cap plates and the bolt serving as a clamping means for holding the bed in adjusted positions. 130
9. A lathe provided with a rockable bed, head and tail stocks carried thereby with the head stock having a driving pulley and the rocking movements of the bed causing movements of the driving pulley toward and from the source of power from which the driving pulley receives motion.
10. A lathe provided with a bed rockable about its longitudinal axis, supporting means for the bed, a pulley mounted upon the supporting means, head and tail stocks mounted on the bed, and a pulley mounted on the head stock in position to receive power from the pulley on the supporting means, and movable by rocking movements of the bed toward and from the first-named pulley. 85
11. A lathe provided with a bed, head and tail stocks fixed thereto, alined spindles mounted in the head and tail stocks, a longitudinally movable rockable spindle mounted in the head and tail stocks in parallel relation to the first-named spindles, a tool carriage mounted on the last-named spindle, a feed screw in the last-named spindle, feeding connections between the feed screw and the tool carriage, and gear connections carried by the head stock for turning the head stock spindle and the feed screw. 95
12. A lathe provided with a bed, head and tail stocks fixed thereto, alined spindles mounted in the head and tail stocks, a longitudinally movable rockable spindle mounted in the head and tail stocks in parallel relation to the first-named spindles, tool carriage mounted on the last-named spindle, a feed screw in the last-named spindle, feeding connections between the feed screw and the tool carriage, and gear connections carried by the head stock for turning the head stock spindle and the feed screw, said feed screw having readily removable connections with the gearing for the removal of the feed screw and interchange with other feed screws, at will. 100
13. A lathe provided with head and tail stocks and head and tail stock spindles, another spindle mounted in the head and tail stocks and slideable longitudinally therein, a tool carriage on the last-named spindle and movable therewith, a feed screw extending into the last-named spindle for imparting longitudinal movement thereto, gearing connections between the head stock spindle and the feed screw, a driving shaft on the head 110

stock, and speed changing gearing between the driving shaft and the head stock spindle.

14. A lathe provided with head and tail stocks and head and tail stock spindles, another spindle mounted in the head and tail stocks and slidably longitudinally therein, a tool carriage on the last-named spindle and movable therewith, a feed screw extending into the last-named spindle for imparting longitudinal movement thereto, gearing connections between the head stock spindle and the feed screw, a driving shaft on the head stock, and speed changing gearing between the driving shaft and the head stock spindle, said speed changing gearing comprising gears of different diameters mounted on the head stock spindle, and other gears of correspondingly different diameters mounted on the shaft carried by the head stock, said shaft being mounted for longitudinal adjustment, and the gears being so spaced as to cause the intermeshing of certain mating gears and the simultaneous throwing out of mesh of other mating gears.

15. In a lathe, a head stock provided with a spindle having a face plate with peripheral gear teeth, and other gears of different diameters on said spindle, a longitudinally movable shaft mounted on the head stock and provided with mating gears for the face plate gear and one of the other gears on the spindle, the spacing of the gears on the shaft being different from that on the spindle, a longitudinally movable spindle mounted in the head stock and provided with a tool carriage thereon, a gear sleeve mounted on the head stock in line with the last-named spindle, a gear wheel mounted on the gear sleeve and movable longitudinally thereof into and out of mesh with one of the gears of the head stock spindle, and a feed screw carried by the longitudinally movable spindle and having means for securing it to the gear sleeve for rotation therewith.

16. In a lathe, a head stock provided with a spindle having a face plate with peripheral gear teeth, and other gears of different diameters on said spindle, a longitudinally movable shaft mounted in the head stock and provided with mating gears for the face plate gear and one of the other gears on the spindle, the spacing of the gears on the shaft being different from that on the spindle, a longitudinally movable spindle mounted in the head stock and provided with a tool carriage thereon, a gear sleeve mounted on the head stock in line with the last-named spindle, a gear wheel mounted on the gear sleeve and movable longitudinally thereof into and out of mesh with one of the gears of the head stock spindle, and a feed screw carried by the longitudinally movable spindle and having means for securing it to the gear sleeve for rotation therewith, the head stock being also provided with direction-

changing gearing movable into and out of engagement with one of the gears of the head stock spindle and with the gear sleeve.

17. A lathe having a bed, head and tail stocks thereon, head and tail spindles carried by the respective stocks, and other head and tail spindles carried by the respective stocks and more distant from the bed than the first-named spindles, the second-named head spindle having means for driving the first-named head-spindle and both tail spindles being independently adjustable in the tail stock, and the second named tail spindle having connections with the first-named tail spindle for the longitudinal adjustment of the first-named tail spindle by the second-named tail spindle.

18. A lathe having a bed, head and tail stocks thereon, head and tail spindles carried by the respective stocks, and other head and tail spindles carried by the respective stocks and more distant from the bed than the first-named spindles, the second-named head spindle having means for driving the first-named head spindle and both tail spindles being independently adjustable in the tail stock, and the second named tail spindle having connections with the first-named tail spindle for the longitudinal adjustment of the first-named tail spindle by the second-named tail spindle, said connections between the two tail spindles being on the side of the tail stock remote from the head stock and in readily removable relation to the first-named tail spindle.

19. A lathe having head and tail stocks and aligned head and tail spindles, another head spindle longitudinally movable in the head stock, and another tail spindle aligned with the second-named head spindle, said head spindles having variable gear connections between them differently spaced apart on the two spindles for causing the meshing of the gear connections in different speed relations by the longitudinal movement of the second-named head spindle.

20. A lathe having head and tail stocks and aligned head and tail spindles, with the tail spindle adjustable toward and from the head spindle, another head spindle longitudinally movable in the head stock, another tail spindle aligned with the second-named head spindle, variable gear connections between the second-named head spindle and the first-named head spindle for driving the latter, another spindle common to both the head and tail stocks and movable longitudinally therewith in parallel relation with the first-named spindles, a tool carriage mounted on said third-named spindle, a feed screw extending into the third-named spindle, gearing connections between the first-named head spindle and the third-named spindle, and feeding connections between the tool carriage and the feed screw.

21. A lathe having head and tail stocks and alined head and tail spindles, another head spindle longitudinally movable in the head stock, another tail spindle alined with 5 the second-named head spindle, variable gear connections between the second-named head spindle and the first-named head spindle for driving the latter, another spindle common to both the head and tail stocks 10 and movable longitudinally therealong in parallel relation with the first-named spindles, a tool carriage mounted in the third-named spindle, a feed screw extending into the third-named spindle, gearing connections 15 between the first-named spindle and the third-named spindle, feeding connections between the tool carriage and the feed screw, and means for rocking the third-named spindle about its longitudinal axis.
- 20 22. In a lathe, a longitudinally movable and axially rockable spindle, a tool carriage mounted thereon, and means for rocking the spindle comprising a sleeve keyed to the spindle and through which the latter is 25 movable longitudinally, said sleeve having a gear segment thereon, and a feeding means for the gear segment carried by a relatively fixed part of the lathe.
23. A lathe provided with head and tail 30 stocks, a longitudinally movable and axially rockable spindle mounted in the head and tail stocks, a tool carriage on said spindle and movable therewith, means for imparting longitudinal movement to the spindle, and means for causing rocking movements 35 of the spindle comprising a sleeve carried by the tail stock and keyed to the spindle, said sleeve having a gear segment thereon, and a worm mounted in the tail stock for 40 engagement with the gear segment.
24. In a lathe, a longitudinally movable spindle mounted for rocking movements about its longitudinal axis, a feed screw extending thereinto, and a tool carriage mounted on the spindle, said tool carriage 45 being provided with a feed nut movable into and out of engagement with the feed screw.
25. In a lathe, a longitudinally movable spindle, a feed screw extending thereinto, 50 and a tool carriage mounted on the spindle, said tool carriage being provided with a feed nut movable into and out of engagement with the feed screw, said carriage having means for causing the movement of the 55 nut comprising a rotatable ring surrounding the spindle and having a spiral groove therein, and the nut being provided with a pin entering the groove.
26. In a lathe, a longitudinally movable 60 spindle, a feed screw extending thereinto, and a tool carriage mounted on the spindle, said tool carriage being provided with a feed nut movable into and out of engagement with the feed screw, said carriage 65 having means for causing the movement of the nut comprising a rotatable ring surrounding the spindle and having a spiral groove therein, and the nut being provided with a pin entering the groove, said tool 70 carriage being also provided with a clamping means for the rotatable ring.

In testimony, that I claim the foregoing as my own, I have hereto affixed my signature in the presence of two witnesses.

BURTON H. CLEMENT.
